POWER-DRIVEN INDUSTRIAL VACUUM CLEANER

Alexander W. Moffat, Beverly Farms, Mass., assignor to
Handling Devices Company, Inc., Brookline, Mass., a
corporation of Massachusetts

Application July 29, 1953, Serial No. 26,183

Term of patent 14 years

(Cl. D9—2)

Fig. 1.

Fig. 2.

Fig. 3.

Fig. 4.

Fig. 5.

Fig. 1 is a perspective view of a power-driven industrial vacuum cleaner embodying my new design;

Fig. 2 is a top plan view;

Fig. 3 is a side view;

Fig. 4 is a front view; and

Fig. 5 is a rear view thereof.

I claim:

The ornamental design for a power-driven industrial vacuum cleaner, substantially as shown.
